FOUNTAIN PEN FILLER

Filed July 14, 1930

Inventor
Paul C. Zieschang

By H. S. M. Glawell

Attorney

UNITED STATES PATENT OFFICE

PAUL C. ZIESCHANG, OF COLUMBUS, OHIO

FOUNTAIN-PEN FILLER

Application filed July 14, 1930. Serial No. 467,744.

This invention relates to improvements in fountain pens and has for its primary object the provision of an improved mechanism, constituting a permanent part of the pen for effecting the complete filling of the ink holding reservoir of the pen. In the ordinary fountain pen there is provided a collapsible sack, and the barrel of the pen is equipped with sack collapsing means. It is a matter of common experience that this customary construction in fountain pens does not permit of complete filling of the ink holding sack with the writing fluid and it is necessary at relatively frequent intervals to refill the pen with the writing fluid. Another objection to the employment of a collapsible sack is that it becomes broken after a very short period of use necessitating frequent replacement thereof.

It is an outstanding object of the present invention to eliminate the ink holding sack from the barrel of the pen and to provide an improved filling mechanism consisting of a plunger which is operable from the upper portion of the pen and which operates to permit of the free flow of ink into the elongated ink chamber of the barrel permitting said chamber to be filled to its maximum capacity with a writing fluid.

It is another object of the invention to provide a fountain pen which is not apt to leak while being carried about and also one which is of positive and rugged, yet comparatively inexpensive construction wherein the pumping mechanism does not add appreciably to the size of the pen or render the same bulky to carry or awkward to manipulate.

A further object of the invention resides in the provision of a fountain pen filling mechanism which includes a pump plunger having attached thereto a flexible gear rack with which is associated suitable gearing provided in the upper end of the pen and which gearing is manipulated by a rotatable cap forming the top of the pen to cause a reciprocatory movement of the plunger within the barrel.

With these and other objects in view, which will appear as the description proceeds, the invention consists in the novel features of

construction, combination of elements and arrangements of parts hereinafter to be more fully described and pointed out in the appended claims.

In the accompanying drawings:

Figure 1 is a vertical sectional view taken through a fountain pen comprising the present invention wherein the upper portion thereof is partly in elevation,

Figure 2 is a transverse vertical sectional view taken on the line 2—2 of Figure 1,

Figure 3 is a similar view of the pen taken at right angles to that disclosed in Figure 2,

Figure 4 is a horizontal sectional view taken on the line 4—4 of Figure 2,

Figure 5 is a similar view taken on the line 5—5 of Figure 2,

Figure 6 is a horizontal sectional view taken on the line 6—6 of Figure 2,

Figure 7 is a side elevation of the gear carrying member positioned at the upper end of the pen.

Referring more particularly to the drawings, the numeral 1 designates the barrel of a fountain pen constructed in accordance with the present invention. The barrel may be formed from any of the customary materials employed in the manufacture of pens of this character and, also, may be of any desired shape, form or appearance, since it is one of the features of the present invention that while a new type of filling mechanism has been provided, yet the standard exterior construction of the pen is not affected thereby. The lower end of the barrel 1 is provided with the usual pen point 2 and the ink guiding feeder 3, the latter being provided with the usual channel or passage 4 by which the writing fluid may be conducted from the ink receiving chamber 5 within the barrel in regulated quantities to the pen point.

The upper end of the barrel 1 is provided with a wall 6 which may be in the form of a plug adhesively united along its side edges to the interior wall of the barrel. Arranged above the plug or wall 6 is a member 7 which is secured to the wall 6 by means of screws or other fastening elements 8 to hold the member 7 in rigid relationship with the wall 6 and the barrel 1 of the pen.

Mounted within a slot formed in the upper end of the member 7 and to one side of the axial center of the pen is a gear 9 which is mounted for rotation around a horizontally arranged pivot member 10 screwed into the body of the member 7. Arranged to intermesh with the gear 9 is a similar gear 11 horizontally arranged and fixed for rotation with a cap member 12 positioned on the upper end of the pen. The cap 12 is formed 10 with a chamber 13 in which the gear mechanism and the member 7 is located and around which the cap member 12 is rotated. To hold the cap member 12 in place upon the upper end of the pen there is provided an 15 annular groove 14 in the member 7 and in which groove is received the inner ends of a pair of screws 14' carried by the side walls of the cap 12. It will be seen that by means of this connection between the cap and the member 7 the former may be rotated yet held 20 in place in connection with the pen and that the rotation of the cap and the gear 11 will transmit a rotary motion to the gear 9.

Arranged to intermesh with the gear 9 is 25 a flexible gear rack 15 which has one end thereof attached to a plunger member 16 and the other free end thereof received within a longitudinally arranged elongated pocket or well 17 provided in the body of the pen to 30 one side of the ink receiving chamber 5. The gear rack 15 which is in the form of a steel ribbon is guided within the arcuate slot 18 formed in the member 7 and is so arranged that the teeth 19 of the gear rack will always 35 intermesh with the gear or pinion 9 to cause the rack 15 to slide longitudinally of the slot. The slot 18 has one of its ends registering with the well 17 and the other with the opening 20 formed in the wall 6.

The gear rack or ribbon 15 may be secured 40 in any suitable manner, as by soldering or brazing the same, to the upper metallic plate member 21 of the plunger 16. Clamped between the plate member 21 and the washer 22 at the lower end of the plunger is a plurality 45 of disks 23 forming the plunger 16 and which disks may be made of soft leather, rubber or other flexible material found suitable for this purpose. The disks 23 may be held in clamped relationship with each other by means of a fastening element 24 and which connects the end members 21 and 22.

In operation, when it is desired to refill the 50 reservoir of the pen with ink, the cap 12 is rotated in a clockwise direction rotating the gears 9 and 11 causing the ribbon or gear 15 and its connected plunger 16 to move downwardly toward the lower end of the barrel. The pen point is then submerged in a body of 55 ink, and the cap 12 is rotated in the reverse or anti-clockwise direction effecting an upward movement of the plunger and drawing the ink upwardly into the reservoir 5, filling the latter completely. The plunger 16

when in an uppermost position will close the opening 20 and form a seal between the plunger and the wall 6, which is provided with an annular rib 25 which will engage with the upper disk 23 of the plunger. When the plunger is drawn into firm contact with the rib 25 an effective seal is provided which will prevent any ink or writing fluid from entering the opening 20 and the operating mechanism positioned within the cap and the upper end of the pen. 70 75

It will be seen from the foregoing that the customary rubber or collapsible sack inside of the barrel has been dispensed with which deteriorates and is a source of nuisance and expense in the present type of fountain pens. The pen, due to the seal between the plunger and the upper end wall of the barrel is completely closed and therefore is not subject to leakage. The operation of filling and emptying is simple and can be carried out readily and quickly, the barrel being flushed out with water in the same manner for cleaning purposes. There is only one part subject to any appreciable wear namely: the washers 23 of the plunger member 16 and these may be readily replaced at small cost. To gain access to the plunger for the replacement of the washers 23 the lower threaded end 26 which carries the pen point and the feeder 3 may be unscrewed and the plunger with its attached ribbon 15 removed from the barrel. 80 85 90

It will be obvious that many changes in the construction, combination and arrangement of parts may be made without departing from the spirit of the invention, and I do not desire to limit the invention to the details shown in the drawings, except as particularly pointed out in the claims. 100 105 110

What is claimed is:

1. In a fountain pen, a barrel including an ink reservoir, a plunger mounted for sliding movement within said reservoir, a rotatable cap member carried by the upper end of said barrel, a gear mechanism within said cap member and mounted for rotation therewith, and a gear rack connecting said plunger and meshing with said gear mechanism whereby upon the rotation of said cap member longitudinal sliding movement will be imparted to said plunger. 115

2. In a fountain pen, a barrel including an ink reservoir, a plunger mounted within said reservoir, a flexible gear rack having one end connecting said plunger and the other end received within an elongated well provided in said barrel to one side of said reservoir, a rotatable cap member carried by the upper end of said barrel, and motion transmitting means between said rack and said cap member for effecting longitudinal sliding movement of said plunger within said reservoir. 120 125

3. In a fountain pen, a barrel including 130

an ink reservoir, a plunger mounted for longitudinal sliding movement within said reservoir, a flexible gear rack attached at one end to said plunger and the other end received within a well formed longitudinally of the barrel and to one side of said reservoir, a member positioned at the upper end of said barrel having an arcuate guideway for said rack, a gear mounted for rotation 10 in said member and meshing with said gear rack, a rotatable cap carried by the upper end of said barrel, and gear means fixed with said cap and meshing with said gear member.

4. In a fountain pen, a barrel including 15 an internal ink reservoir and an elongated well, a plunger element slidably received within said reservoir, a flexible gear rack connected at one end to said plunger element and the other end received within said 20 well, a gear meshing with said gear rack, and means formed exterior of said pen for rotating said gear.

5. In a fountain pen, a barrel including an ink reservoir and a closure at one end of 25 said barrel having an opening therein, there being an elongated well formed in said barrel to one side of said reservoir and arranged parallel therewith and an arcuate passage-way connecting said well and reservoir by 30 way of the opening formed in said closure, a ribbon-like gear trained through said passage and having one of its ends received within said reservoir, a plunger element attached to the latter end of said ribbon and slidably 35 positioned within said reservoir, a rotatable cap member carried by the upper end of said barrel, and gear means between said cap and said ribbon.

6. In a fountain pen, a barrel including 40 an ink reservoir, a reciprocatory plunger element positioned within said reservoir, a flexible member having one end connecting said plunger element and the other end received within an elongated well provided in the 45 barrel to one side of said reservoir, a rotatable cap member connected by the upper end of said barrel, and means formed with said cap and flexible member for effecting a longitudinal sliding movement of said plunger 50 element upon the rotation of said cap member.

7. In a fountain pen, a barrel including an ink reservoir and an elongated well, a member positioned at one end of said barrel 55 and provided with an arcuate guideway connecting said reservoir and said well, a ribbon-like gear element positioned within said guideway and having one end thereof received within said well and the other end 60 within said reservoir, a piston slidably received within said reservoir and connecting said ribbon, a gear carried by said member and meshing with said ribbon-like gear element, a rotatable cap mounted for rotation 65 at the upper end of said barrel, a gear ar-

ranged for rotation within said cap and meshing with said first named gear, and means for holding said cap in connection with said member.

In testimony whereof I affix my signature.

PAUL C. ZIESCHANG.
